UNITED STATES PATENT OFFICE.

EDWARD B. REILLY, OF ATLANTIC CITY, NEW JERSEY, ASSIGNOR OF FOUR-FIFTHS TO
HARRY R. YOUNG, OF ATLANTIC CITY, NEW JERSEY.

SUBMARINE BOAT.

1,244,242.

Specification of Letters Patent. Patented Oct. 23, 1917.

Application filed May 4, 1916. Serial No. 95,357.

To all whom it may concern:

Be it known that I, EDWARD B. REILLY, a citizen of the United States, residing at Atlantic City, in the county of Atlantic and 5 State of New Jersey, have invented certain new and useful Improvements in Submarine Boats, of which the following is a specification.

This invention relates to certain new and 10 useful improvements in submarine boats and it has for its objects among others to provide a novel construction of hull whereby the boat may be better balanced and more easily controlled, whereby it may be made 15 to automatically dive or rise by the shifting of the center of gravity, and, consequently, make the resistance of the water upon its inclined deck greater or less at any regular velocity, and as the velocity becomes greater 20 the resistance increases proportionate to the shifting of the center of gravity.

I construct the boat of such a shape as to accomplish this object, without the employment of planes or rudders or any other form 25 of external attachment. In my boat there are no lateral projections, everything being confined within the cross sectional area of the boat. The boat is constructed with a flat 30 upper surface extending from its widest point to the bow and downwardly at an angle to the longitudinal axis of the boat. This flat surface extends from the conning tower to the prow of the boat. This offers great resistance to the upward or rising 35 movement of the prow. The stern is formed upon lines which are novel and which tend to offer less resistance, being curved downwardly and rearwardly, from the rear of the conning tower to the extreme stern of the 40 boat.

By altering the resistance of the water upon the boat, I can cause it to rise or sink to any desired depth.

The boat may be propelled by any suitable means, such, for instance, as by the generation of steam by means of burning crude oil, gasoline, coal oil or any of its refined products, or any other burning fuel which can be converted into units of exertion. The 45 present invention, however, pertains to the shape of the body regardless of the manner in which it is propelled or the means for or manner of shifting its center of gravity.

Other objects and advantages of the invention will hereinafter appear and the

novel features thereof will be particularly pointed out in the appended claims.

The invention is clearly illustrated in the accompanying drawings, which, with the numerals of reference marked thereon, form 60 a part of this specification, and in which

Figure 1 is a side elevation of a submarine constructed in accordance with my present invention.

Fig. 2 is a view looking at the bow.

Fig. 3 is a view looking at the stern.

Fig. 4 illustrates the cross sectional form of the boat at or near midship, the conning tower being removed.

Like numerals of reference indicate like 70 parts throughout the several views.

Referring to the drawings,

1 designates the boat proper, the interior of which does not pertain to the present invention and hence the exterior appearance 75 only has been illustrated. As will be seen upon reference to the different figures of the drawing, the boat has a substantially smooth exterior, being constructed without vanes or blades or other extraneous means, 80 and, in fact, devoid of all means or projections extending beyond the sides or ends of the boat and, hence, avoiding liability of such projections, as vanes or the like, retarding the progress of the boat or endangering the same by coming in contact with rocks or other obstructions, as well as tending to necessitate a wider channel through which the boat can pass.

As will be seen in Fig. 1, the greater dimensions of the boat are to the rear of the transverse center thereof. The boat is formed with a portion 2 to receive the conning tower 3, which latter and its appurtenances, however, form no part of the present invention and may be of any well-known or approved form of construction operating in any well-known way.

Forward of this portion 2 there is a comparatively narrow projection 4 having a flat 100 upper face 5 and which may constitute a deck which may be readily reached from the conning tower, this projection 4 having convergent sides 6, 6, as seen best in Fig. 2, and the forward end of which is preferably 105 concaved or upon inwardly receding curved lines, as seen at 7 in Fig. 1.

Forward of this member 4, the hull is formed with a substantially flat upper portion, as seen at 8, extending the full width 110

of the hull to the prow 9, as seen in Fig. 2, the forward end thereof being inclined, as seen at 10, and terminating at a point 11. The bottom of the boat is rounded, as seen 5 in Figs. 2, 3 and 4, the same extending backward to the point 12, Fig. 4 representing a vertical cross section of the hull at a point slightly forward of the point 12, and from which point the bottom extends rearwardly 10 and upwardly upon curved lines, as seen at 13, the upper face of the portion to the rear of the portion 2 being upon curved lines, as seen at 14, and extending for the full width of the hull at the rear of the conning tower, to a point 15, as seen in Figs. 1 and 3.

As shown in the present instance, twin propellers 16 are provided for the propulsion of the boat and these may be driven in any suitable or well-known way.

20 The line $a-a$ in Fig. 1 designates the water line when the boat is not submerged. The hull is so constructed that the proportion of the weight is such that when in the position seen in Fig. 1, the broad flat upper 25 surface 8 of the prow of the boat offers sufficient resistance to the tendency of the boat to rise at the bow, to keep the same down so that the boat will ride with the bottom at substantially the angle to the horizontal, as 30 seen in said Fig. 1. Increased speed and consequent greater tendency of the boat to rise at the bow are compensated for by the resistance offered by the broad and flattened forward portion of the upper surface of 35 the boat. Variations in speed, and shifting of the center of gravity regulates the diving or rising of the boat by the consequent resistance of the water upon the inclined deck; as the velocity becomes greater the 40 resistance increases proportionately. This shifting of the center of gravity may be accomplished in any suitable manner, by the concentration of any weight at any one particular position on the boat, and the velocity 45 of the boat is controlled by whatever means of propulsion the boat may be equipped with. The shape of the hull is the controlling element in the rise and fall of the boat.

The construction is such as to not only 50 slightly restrict the tendency of the bow to sink or to vibrate up or down, but it aids in insuring a more steady diving and doing away with tendency to wabble while submerged.

55 By reason of the particular construction of the boat, all extraneous projections, such as vanes or the like, which would tend to retard its progress, are avoided, as well as liability of injury to the boat by the presence of such projections. The absence of 60 these lateral projections enables me to provide a boat with a smooth unobstructed outer surface, giving every advantage obtainable for maximum speed with minimum 65 power.

From the foregoing, it will be seen that I have devised a boat whose shape is such that it uses the resistance of the water to submerge or rise, and while the structural embodiment of the invention as herein disclosed is what I at the present time consider preferable, it is evident that the same is subject to changes, variations and modifications in detail, proportion of parts, etc., without departing from the spirit of the invention 70 or sacrificing any of its advantages and which details may be changed from time to time according to requirements. I, therefore, do not intend to restrict myself to the precise construction, arrangement and proportion of parts hereinbefore disclosed, but reserve the right to make such changes, variations and modifications as come properly within the scope of the protection 75 prayed.

It is evident that the shifting of gravity may be done by the concentration of any weight at any particular part of the boat and which weight can be a suitable carriage in which may be placed excess baggage 80 which when used can be replaced by water.

What is claimed as new is:—

1. A submarine boat having a flat upper surface extending from its widest point to the bow and having its upper surface aft 95 of the conning tower curved downwardly and rearwardly.

2. A submarine boat having a flat upper surface extending from its widest point to the bow and downwardly at an angle to 100 the longitudinal axis of the boat.

3. A submarine boat having a flat upper surface extending from its widest point to the bow and downwardly at an angle to the longitudinal axis of the boat and having its 105 upper surface aft of the conning tower curved downwardly and rearwardly.

4. A submarine boat having a flat upper surface extending from the conning tower to the bow and downwardly at an angle to 110 the longitudinal axis of the boat.

5. A submarine boat having a flat upper surface extending from the conning tower to the bow and downwardly at an angle to the longitudinal axis of the boat and having 115 its upper surface to the rear of the conning tower curved downwardly and rearwardly.

6. A submarine boat having a flat upper surface extending from its widest portion adjacent the conning tower to the bow and downwardly at an angle to the longitudinal 120 axis of the boat.

7. A submarine boat having a flat upper surface extending from its widest portion adjacent the conning tower to the bow and downwardly at an angle to the longitudinal axis of the boat, said flat surface having intermediate its ends a deck portion with convergent sides and concaved forward end. 125

8. A submarine boat having a flat upper 130

surface extending from its widest portion adjacent the conning tower to the bow and downwardly at an angle to the longitudinal axis of the boat, said flat surface having 5 intermediate its ends a deck portion with convergent sides and concaved forward end, the upper surface of the boat to the rear of the conning tower being curved downwardly and rearwardly and extending for

10 the full width of the hull.

9. A submarine boat having a smooth hull with its broad upper surface forward of the center of the boat flat and tapered toward the bow, with a flat deck extending 15 therefrom and terminating adjacent the conning tower, said upper surface forward of said deck extending downwardly at an angle to the longitudinal axis of the boat.

10. A submarine boat having a smooth hull with its broad upper surface forward 20 of the center of the boat flat and tapered toward the bow, with a flat deck extending therefrom and terminating adjacent the conning tower, said upper surface forward of said deck extending downwardly at an angle 25 to the longitudinal axis of the boat, the rear upper surface of the boat to the rear of the conning tower being formed upon lines curved downwardly and rearwardly and to opposite sides of the boat.

In testimony whereof I affix my signature in the presence of two witnesses.

EDWARD B. REILLY.
